UNITED STATES PATENT OFFICE.

CARL NOHSE, OF BERLIN-PANKOW, GERMANY.

AUTOMATIC STOP FOR RAILWAY WAGONS.

Application filed September 9, 1925, Serial No. 55,408, and in Germany September 3, 1924.

This invention relates to improvements in automatic stops for cars running on rails.

It is commonly known to arrange on braking inclines automatic stops built in 5 on the track and designed to stop cars which exceed a predetermined maximum speed at the downward journey. In this stop an oscillatably mounted releasing- or abutment element, similar to an elbow lever and acted 10 upon by the front axle of the car, acts directly upon a separate catch lever which is oscillatable independently of other elements so that this catch lever is brought into a position to catch the second axle of the 15 car if the car which is running downward has exceeded a predetermined speed.

Numerous forms of construction of such mechanisms are known, and amongst these, 20 constructions in which the abutment member is rigidly connected with the catch claw to form an elbow lever. In other forms of construction the abutment element is, together with the releasing element, separate 25 from the catch claw and independent from it but arranged on a common bolt. Or the abutment element has been arranged by itself and the catch claw with the releasing element on a separate axle.

The systems mentioned above are bound 30 to determined service conditions and consequently limited as regards applicability. Some of them work perfectly as long as the speed of the cable or chain does not exceed 1 meter per second. A catching device of 35 known type has been proved as specially adapted in all cases where the speed does not exceed 1 meter per second, said device comprising an oscillating releasing element similar to an elbow lever and acting di- 40 rectly upon the catch lever oscillatably but separately mounted on the same axle, this satisfactory result being due to the stable construction and to the simplicity of the individual elements specially adapted for 45 the rough mine-service. This device does however not work satisfactorily on downward inclines as soon as the speed exceeds 1 meter per second, as at this speed the

catch lever is thrown into the catching position.

It has been proposed to avoid this inconvenience by making the catch claw heavier up to the constructive limit and by making the travel of the catch lever to the catching position so much longer as the construction 50 of the cars permits, in considering however that the second car axle had to be caught under any circumstances. It has been further proposed to give to the abutment lever so much idle movement that the catch claw 55 is thrown into the catching position at the instant when the first wheel axle has almost left the abutment lever. But all these modifications were constructively limited and could give little satisfaction as the impulse 60 of the downward rolling cars is so great that, notwithstanding the utilization of all proposed improvements, no technical progress 65 could be obtained.

This invention relates to an automatic 70 stop for cars running on tracks which is adapted for any speed of the car be it 1 to 10 meters per second or more. It presents further the advantage that the mechanism can be adjusted in accordance with 75 the actual speed. It happens frequently that the conveying speed has to be increased on account of the accelerated working of the mine. In this case the stop device can be adjusted to the higher speed as the releasing element for the catch claw has its 80 own pivot bolt which may be arranged at a more or less great distance from the pivot bolt of the catch claw within the range of this catch claw, the catch tappet for the 85 catch claw being adjustable at a greater or lesser distance from the pivot bolt of the releasing element.

An embodiment of the invention is shown, 90 by way of example, on the accompanying drawing in which—

Fig. 1 shows diagrammatically the device, the bolt of the combined abutment and releasing element being arranged under the 95 bolt of the catch lever.

Fig. 2 is a similar view as Fig. 1, the

bolt of the abutment and releasing element being arranged at the side of the bolt of the catch lever.

Fig. 3 shows the safety device in the position of rest, the abutment element being shown in dash lines in the position which it assumes when the skip ascends, the releasing element being omitted.

Fig. 4 illustrates the angle of oscillation of the abutment- and releasing element and the stroke of the catch lever at descending skip, the catching position being indicated in dash-lines.

Fig. 5 is a plan view.

Fig. 6 shows the device inserted on the track; the car running down an incline passes the device without being stopped.

Fig. 7 is a detail view of the releasing element.

Fig. 8 is an enlarged transverse sectional view illustrating the construction and manner of mounting the releasing mechanism.

Fig. 9 is a detail view of the abutment and stud of the releasing mechanism.

When the abutment lever oscillates in Fig. 1 through the angle H G H' the catch lever E F moves into the position E F', the pivot point H of the abutment lever travels at this occasion from H to H'. The lever arm of the

catch-lever weight has, in the position of rest, the length F H; after having oscillated into the position E F' the length of the lever arm is $=F' H' = F H + H K$, the amount added being H K. In Fig. 2, M P O indicates the

position of rest of the catch lever and R P the position of rest of the abutment lever. At an oscillation of the abutment lever through the angle P N P' the catch lever moves into the position M P O', the increase

of the lever length of the catch lever amounting to P Q in the position indicated in dash-and dot lines at an oscillation of the abutment lever through the angle P N P' the catch lever moves into the position M P O', the increase

of the lever length of the catch lever amounts to P R. Herefrom results that the increase of the catch lever movement is the greater the greater the angle of oscillation of the abutment angle becomes. Trans-

ferred to practice this means that the normal speed of the skips when descending can be greater than is the case with a constant catch lever moment. The catch lever moment is constant in all safety devices in which the

catch lever and the abutment lever are mounted on a common bolt and in which the abutment lever acts as releasing element for the catch lever. The single pivot bolt which at

first seems to be an advantage has the inconvenience of necessitating a moderate drawing speed.

In a traverse a (Figs. 3, 4, 5) of cast steel or profile iron the pivot bolt e is mounted in a strong bearing lug b , the catch lever d being loosely mounted on said pivot bolt e .

A pivot bolt e for the abutment- and releasing element f is, for instance, arranged underneath the pivot bolt e . The releasing stud h which grips under the catch lever d is fixed on f and may be arranged so that it can be adjusted to a position more or less distant from the pivot bolt e . The abutment- and releasing element carries at its lower end the mass g serving as counterweight to maintain the abutment- and releasing element in the position of rest perpendicular to the inclined plane. In the position of rest the catch lever d rests upon a stop i arranged on the traverse a . In the catch position the catch lever bears against a bracket k connected with the traverse a . For adjusting the pivot e the bearing lug b and the opposite bearing lug for the pivot e may have apertures in which the pivot e can be adjusted and secured by means of screws. For adjusting stud h the releasing element f may for instance have an aperture m with which the stud h engages so that it can be adjusted and fixed by means of a screw at a greater or shorter distance from the pivot e . The pivot e for the abutment and the releasing element f may be arranged either beneath the pivot e or at the side thereof.

At the normal descending movement of the skip the combined abutment- and releasing element f oscillates and the catch lever d is lifted for a certain amount through the intermediary of the releasing stud h (Fig. 4). After the skip has passed the elements are returned into the position of rest by the action of the counterweight g or of the weight of the catch lever. When a skip gets detached from the cable or chain the

first wheel axle of the skip will strike strongly against the abutment- and releasing element f so that the catch lever d is thrown into the catching position and catches the skip at the second wheel axle. The abutment lever f remains absolutely relieved and bears in the catching position against the caught axle.

I claim:—

1. An automatic safety device mounted on the track of inclined planes designed to catch skips which exceed at the descending a pre-determined maximum speed, comprising in combination a catch lever pivotally mounted on the track, a releasing element having a stud arranged to engage and actuate the catch lever, a pivot bolt for said releasing element mounted at a certain distance from the pivot bolt of said catch lever.

2. An automatic safety device mounted on the track of inclined planes designed to catch skips which exceed at the descending a pre-determined maximum speed, comprising in combination a catch lever pivotally mounted on the track, a releasing element for said catch lever, a pivot bolt for said releasing ele-

ment adjustably mounted at a certain distance from the pivot bolt of said catch lever.

3. An automatic safety device mounted on the track of inclined planes designed to catch skips which exceed at the descending a predetermined maximum speed, comprising in combination a catch lever pivotally mounted on the track, a releasing element

for said catch lever, a pivot bolt for said releasing element mounted at a certain distance of the pivot bolt of said catch lever, and a releasing stud on said releasing element adjustable with regard to said pivot bolt of said releasing element. ¹⁰

In testimony whereof I affix my signature.
CARL NOHSE.
